UNITED STATES PATENT OFFICE.

SILAS A. MORTON, OF FRIENDSHIP, MAINE.

ICE-ELEVATOR.

SPECIFICATION forming part of Letters Patent No. 256,155, dated April 11, 1882.

Application filed February 28, 1882. (No model.)

To all whom it may concern:

Be it known that I, SILAS A. MORTON, a citizen of the United States, residing at Friendship, in the county of Knox and State of Maine, have invented certain new and useful Improvements in Ice-Elevators; and I do hereby declare that the following is a full, clear, and exact description of the same, reference being had to the annexed drawings, making a part of this specification, and to the letters and figures of reference marked thereon.

Figure 1 of the drawings is a perspective view of my invention, and Fig. 2 a top plan view of the truck and its attachment.

The present invention has relation to certain new and useful improvements in machines for raising and elevating ice from ponds and rivers; and the object thereof is to provide a simple and effective means by which the ice, after being cut into cakes or pieces of the required size, is carried from out the water up a suitable railway to the ice-house or place of deposit, where it is packed. These objects I attain by the construction substantially as shown in the drawings, and hereinafter described.

In the accompanying drawings, A represents two inclined tracks which extend to the ice-house, said tracks at their lower ends connecting with a horizontal trough, B, for receiving the cakes of ice while in the water.

Narrow joists or strips a form a bed to support the cakes of ice as they are being carried to the place of deposit. The strips a are disposed horizontally within the trough B, and then are inclined upward a certain distance, and again horizontally the required distance to the ice-house. Timbers b keep the cakes of ice separated and from striking against each other, the trough B being of any desirable width to receive two, three, or more cakes of ice, as found desirable.

A truck, C, of any desirable construction, and provided with the usual truck-wheels, c, rides upon the tracks A, it being hauled by a rope or chain from a donkey-engine or horse-

power. To the truck C are swiveled or pivoted arms e, of the desired length, having connected to the outer ends a beam, D, thereby enabling the cross-beam to have a motion up and down by the swinging of the arms. The cross-beam 50 or head D has projecting from its outer side curved rods f, and upon its inner side spurs g, which come in contact with the end of the cakes of ice and prevent the cross-beam or head from being pulled over the end of the cakes during 55 the process of elevating them.

The cakes of ice, which are represented at x, are in position to be elevated, and as the truck C descends the track A the curve in the rods f, as they strike the inner end of the cakes x, will 60 cause the cross-beam D to be elevated over the upper surface of the cakes until the beam is carried by the truck over the outer or opposite end of the cake, as shown in Fig. 1. In this position the truck C is carried up the inclined 65 tracks A, taking with it the cakes of ice, which are carried to the place of deposit.

Having now fully described my invention, what I claim as new, and desire to secure by Letters Patent, is—

1. In an ice-elevator having the usual inclined tracks and bed for supporting the cakes of ice, the combination, with the truck C, of the swinging arms e and cross-beam or head D, carrying the curved rods f, substantially as 75 and for the purpose set forth.

2. The combination, with the inclined tracks A, horizontal trough B, strips a, and timbers b, of the truck C, having pivoted thereto arms e, carrying cross-beam or head D, curved rods f, 80 and spurs g, substantially as and for the purpose specified.

In testimony that I claim the above I have hereunto subscribed my name in the presence of two witnesses.

SILAS A. MORTON.
